HAT BRIM FINISHING MACHINE

D. Ivan Behmer, Lititz, Pa.

Application December 30, 1946, Serial No. 719,195

20 Claims. (Cl. 223—20)

1

This invention relates to improvements in hat brim finishing machines, and more particularly to an improved brim pouncing machine as the term "pouncing" is used in its broad sense to embrace the various abrading, as by sand-papering or clothing, operations practiced on the brim of a felt hat in the finishing thereof.

Generally stated, the invention contemplates and aims to provide a direct-drive type of brim pouncing machine capable of achieving high tool speeds, which is characterized by improved and simplified design and by compact, streamlined construction throughout, which is easy to control and operate, which is effective and efficient in operation, which produces a uniform and superior hat brim finish, and which is equally efficient in performing all of the various back and front-shop operations required in the finishing of the brim of a felt hat. A more particular object of the invention is the provision of a direct drive type of hat brim pouncing machine in which high tool speeds can be obtained in a safe, dependable and effective manner and with a minimum of vibration. Another object of the invention is the provision of a hat brim pouncing machine of the type wherein the tool carrying arms are driven directly from the motor shaft, which employs an improved means of transmitting drive from the motor to the tool carrying arms and of imparting separation and approach motion to the arms while the machine is running, as required to present the brims of the hats being worked to the action of the pouncing tools and to remove them from the machine upon completion of the pouncing operation, without stopping and/or starting the motor.

A still further object of the invention is the provision of a hat brim pouncing machine capable of achieving positive, calibrated control of brim thickness, and which is further so constructed and arranged that the tools operate under adjustable spring pressure, with the pressure adjusting means being conveniently located and easily operated.

The invention also aims to provide a brim pouncing machine employing an improved and simplified brim feeding mechanism of the type employing positively driven upper and lower feed rollers cooperating to grip and progressively feed a hat brim to the action of the pouncing tools, which is characterized by a simple yet effective feed roller drive eliminating belts, sprockets, chains and the like, and which incorporates roller mountings permitting relative separating and approach movements to be applied to the rollers while in motion.

Another important object of the invention is the provision of an improved foot treadle control capable of interrelating the separating and approach movements of the pouncing tools and

2

the feed rollers in such manner that the feed rollers move to their closed or brim feeding position prior to the closing of the tools to their normal working position with respect to the brim, and that the pouncing tools separate prior to separation of the feeding rollers, thereby to make impossible uneven sanding or abrading action, and at the same time leaving the operator's hands free to insert and withdraw the hat while the machine is in motion.

The above and other objects and features of advantage will be apparent from the following description of the invention, taken with the accompanying drawings illustrating a preferred physical embodiment thereof, wherein—

Fig. 1 is a part-sectional plan view of a brim pouncing machine according to the invention, the section being taken along line 1—1 of Fig. 3;

Fig. 2 is a part sectional front elevation of the machine of the invention, the view illustrating details of the tool arm and feed roller driving and separating means;

Fig. 3 is a part sectional side elevation of the machine illustrating the mounting of the eccentric cams in the tool carrying arms and the driving means therefor;

Fig. 4 is a top plan view of the feed roller assembly with certain parts thereof shown in section;

Fig. 5 is a detail view illustrating the feed roller assembly in vertical section;

Fig. 6 is an enlarged part sectional view illustrating certain details in the construction and mounting of the drive shaft extension; and

Figs. 7 and 8 are longitudinal and transverse sections, respectively, taken through one of the pouncing tools, Fig. 7 illustrating a preferred mounting of the pouncing tools to provide for their angular adjustment.

Referring to the drawings, wherein like reference characters designate like parts throughout the several views, reference character 10 indicates an upright open-ended machine housing of generally rectangular section which is supported at its four corners on floating suspension mounts each illustratively consisting of a pair of upper and lower rubber blocks 11, 11a secured against the top and under faces of a horizontal lug 12 formed at each inner corner of the housing by a through bolt 13 functioning also as an anchor bolt for securing the housing to a floor or other horizontal surface.

The housing is closed at its top by the horizontal plate 15 of a head casting 14 which also includes an upright cowl-shaped neck 16 whose upper end extends forwardly and terminates in a cast bearing sleeve 17 having its axis vertically disposed.

Contained within the housing 10 is a driving motor 20 having its shaft 21 vertically disposed.

As best seen in Fig. 2, the motor is secured to an annular head casting flange 15a which depends from the head plate into the machine housing. The upper or head end of the motor shaft 21 projects through an opening provided therefor in the head plate 15 and its projecting end splined as at 22. The lower or tail end of the shaft projects into a motor frame extension casting 24 affixed to the motor housing and carries a power take-off worm 25 for driving the brim feeding rollers, as will be hereinafter described.

Upper and lower pouncing pads or tools generally designated 28, 30 have their operative faces oppositely disposed in the usual manner whereby to operate on the opposite faces of a hat brim inserted therebetween, said faces being replaceably covered with a suitable abrasive material selected for the particular pouncing or abrading treatment to be given the hat brim. The tools 28, 30 are carried at the free ends of upper and lower arms 32, 34, respectively, which are mounted for compound oscillating and reciprocating motion in opposite directions whereby their free ends and hence the pouncing tools move oppositely to one another in closed generally elliptical paths of motion. To provide such a mounting, the rear ends of said arms are pivotally connected by vertically aligned wrist pins 35, 36 to upper and lower fulcrum blocks 37, 38 (Figs. 1 and 3), slideable in fore and aft direction in a vertically disposed, channel-shaped bearing shoe 40 which is bolted to the front face of the neck 16 of the head casting. Accordingly, the tool carrying arms 32, 24 may reciprocate by a limited amount in the direction of their axes and may also oscillate laterally about the common axis of the wrist pins 35, 36. Moreover, due to the vertical motion permitted at least the upper bearing shoe 35 in the bearing block 40, the arms are mounted for separating and approaching motion, that is to say, the upper arm 32 may raise and lower with respect to the lower arm 34, when so actuated.

Considering now the means for imparting the aforesaid compound motion thereto, the arms 32, 34 are formed intermediate their ends with the eccentric enlargements designated 32a, 34a (Figs. 1 and 3). Contained in the eccentric enlargement 34a of the lower arm 34 is a rotary eccentric cam 42 whose bore is provided with driving splines 43, and into which extends the splined upper extension 22 of the motor shaft 21. The eccentric cam 42 is journaled for rotation in spaced upper and lower anti-friction ball bearings 44, 45 secured in place in the arm enlargement as by inner and outer lock bushings 47, 48. Accordingly, drive from the motor 20 is transmitted to the eccentric cam 42 through the splined driving connection between cam and motor shaft, with rotation of the eccentric cam imparting a compound reciprocating and lateral oscillating motion to the arm 34 and a corresponding elliptical motion to the tool 30.

As seen in Figs. 2 and 3, the splined motor shaft extension 22 extends into the eccentric cam 42 for approximately half the axial length only of its splined bore. Extending into the other or upper end half of the bore is the lower splined end 49 of a floating drive shaft extension 48 which is driven from the eccentric cam 42 through its splined driving connection therewith. Intermediate its ends the shaft extension 48 carries a solidly mounted rotary eccentric cam 50 for actuating the upper tool carrying arm 32. As best seen in Fig. 3, the eccentric cam 50 is arranged

180° out of phase with respect to the eccentric cam 42 whereby the arms oscillate in opposite directions, and is journaled for rotation in spaced upper and lower anti-friction ball bearings 51, 52 contained in the eccentric enlargement 32a of the upper arm 32 and secured in place therein by inner and outer lock rings 53, 54.

10 The drive shaft extension 48 is provided with an external thrust shoulder 55 on which the lower end face of the eccentric cam 50 is supported, whereby as the shaft extension is bodily projected upwardly it carries with it the eccentric cam 50. As the latter is vertically fast in arm enlargement 32a and hence to arm 32, any 15 upward movement imparted to the eccentric cam 50 is transmitted to the upper arm 32 and hence to the pad or tool 28 carried at the free end thereof, the inner or restrained end of the arm and its fulcrum block 37 meanwhile sliding vertically in the fulcrum shoe 40. Accordingly, rotation of cam 42 as described effects rotation of the upper cam 50 to impart compound reciprocating and oscillating motion to the upper arm 30 and elliptical motion to the tool 28. Due to the 20 opposite phase relationship of eccentric cams, such tool motion is in the opposite direction to that applied to the tool 30. Moreover, the floating drive connection between drive shaft extension 48 and eccentric cam 42 permits separating 25 and approach motion to be applied to the upper arm and tool carried thereby with respect to the lower arm and its tool.

25 By reference to Fig. 3, the eccentric cam 50 is extended above the arm 32 so as to enter the bearing sleeve 17 of the head casting 14. The drive shaft extension 48 is further extended into the bearing sleeve 17 and at its upper end is journaled for rotation in a floating bearing assembly including anti-friction ball bearings 58, 40 59 contained in a bearing sleeve 60 having sliding bearing in a fixed wear sleeve 61 secured within the head casting sleeve 17. The fixed wear sleeve 61 is externally shouldered adjacent its upper end as at 62, the resulting shoulder 45 abutting on an internal shoulder provided in the bore of the head casting sleeve, against which the sleeve 61 is locked in said bore by a lower lock ring 63. A suitable oil retainer assembly 64 is effective between the extended upper end of the eccentric cam 50 and the fixed wear sleeve 61, as shown.

50 A flanged shaft ring 66 (Fig. 6) is disposed above the uppermost end of upper bearing 58 and mounts a thrust bearing 67 against whose upper race reacts a tension spring 68 contained 55 within the bore of a cap nut 70 which is screwed into and closes the bore of the head casting sleeve 17 as shown. The tension spring encircles a stem 69 whose lower end is bored and interiorly 60 threaded so as to thread on to the threaded upper end of the shaft extension 48. The stem projects through the cap nut and its upper projecting end 69a may be knurled as shown to provide a hand or tool grip, which permits manual 65 turning of the shaft extension 48 and main shaft 21 as is desirable in mounting and adjusting the tools, for example. It will be observed that the tension spring 68 exerts downward pressure on the bearing sleeve assembly and hence on the 70 drive shaft extension 48 which in turn transmits and applies this spring pressure to the upper arm 32 and its tool 28. The tension of spring 68 effective on the tool 28 may be adjusted by the simple operation of screwing down or up on the 75 cap nut 70.

According to the invention, relative separating and approach motion is applied to the oscillating arms 32, 34, and hence to the tools 28 and 30, while the machine is in operation. To this end, means are provided to effect relative separation of the motor shaft 22 and its floating extension 48. Referring to Fig. 2, the motor shaft is axially bored throughout its full length to receive a control rod 75 supported in suitable end bearings, and whose upper end extends into the bore of the cam eccentric 42 and is provided with a ball-point 76 adapted to bear against the lower end face of the floating drive shaft extension 48. Upon the control rod 75 being positively actuated in upward direction, the shaft extension 48 and parts carried thereby, including the upper arm 32, are bodily raised against the action of spring 68, thus to effect separation of the tools 28, 30, as is required to insert and withdraw the brim of a hat being treated. Lowering movement of the control rod 75 results in a corresponding lowering movement of the upper arm 32 and its tool 28 in response to the action of spring 68.

The aforesaid actuation of the control rod 75 in upward direction is effected through a treadle control mechanism now to be described. Referring to Figs. 1 and 2, a foot treadle arm 80 is mounted to turn on the axis of a stud 81 carried by a bracket 83 which, illustratively, is fixed to the lower right rear corner of the machine housing 10. Rigidly affixed to the treadle arm is an upright connecting rod 84 whose upper end is threaded to receive spaced adjusting and lock bolts 85, 85a for securing the outer end 87a of a first degree lever 87 being fulcrumed intermediate its ends by a pin 88 carried in a downward extension of a fulcrum ring 89 which is fixedly secured to the motor frame extension casting 24. The opposite or inner end portion of the lever 87 lines up with a ball-point 90 provided on the lower end of a stem which projects downwardly from a floating bearing housing 91 containing a step bearing 92 which supports a fitting 93 rigidly affixed to the lower end of the control rod 75. The bearing housing 91 operates in an adjusting gland nut 94 having cup formation whereby, in addition to its adjustment function, the nut serves also to provide dash-pot action which prevents a too rapid lowering of the tool carrying arm 32.

From the construction so far described, it will be seen that when the treadle arm 80 is depressed, the inner end of lever 87 moves upwardly and effects corresponding upward movement of the bearing housing 91 and hence of the control rod 75. Upward movement of the control rod is in turn applied through upper oscillating arm 32 to the tool 28, thereby to effect separation of the tools 28 and 30. By proper proportioning of the parts, the amount or degree of tool separating motion is such as to permit ready insertion and withdrawal of the brim of a hat therebetween. Upon foot pressure being released from the treadle, the upper arm 32 lowers under the action of spring 68 and its tool 28 moves into operative position with respect to tool 30 carried by the lower arm 34. It will be observed also that upon release of foot pressure applied to the pedal arm 80 the tension of spring 68 is transmitted through the control rod 75 to lever 87 in direction as to effect raising of the outer end 87a of the lever 87 and return of the treadle arm to its normal raised position.

According to a further feature of the inven-

tion, means are provided for adjusting the spacing between the operative faces of the tools 28, 30, as determined by the amount which arm 32 can lower with respect to arm 34. In this connection, it will be noted that in their operative or working position the tools are normally maintained in spaced relation by an amount which is fixed by the vertical position of the floating drive shaft extension 48 with respect to the vertically fixed drive shaft 20. Referring to Fig. 2, it will be seen that the outer end 87a of the lever 87 lines up with the ball-point 95 provided at the lower end of a control rod 96 whose upper end extends through the horizontal head plate 15. Said control rod is supported adjacent its upper end in a thrust bearing 97 and adjacent its ball-point end by a bracket 98 secured to the motor frame extension casting 24. The upper edge surface of the lever 87 may be provided with a concavity 95a providing a seat for the ball-point 95. The extending upper end of the rod 96 is threaded into a calibrating knob 100 which is turnable in desired increments to adjust the vertical position of the rod and hence of ball-point 95. To secure the control rod in adjusted position, there is provided a key lock 101 operating in a vertical key-way 102 provided in the rod adjacent its lower end. Accordingly, the full raised position of the inner end 87a of lever 87 and hence of treadle arm 80 is determined by the vertical setting of the ball-point 95 as established by the setting of the calibrating knob 100. Inasmuch as the lowermost position of the control rod 75 and hence of the floating drive shaft extension 48 is a direct function of the full raised position of the outer end of lever 87 as determined as aforesaid, it will be seen that the setting of knob 100 determines the normal spacing between the operative faces of the tools 28, 30. Moreover, since the spacing between pouncing tools determines the brim thickness of the hat being worked, the described arrangement provides simple and effective means whereby final brim thickness may be controlled as well as a means for varying the pouncing action of the tools from coarse to fine pouncing, for example.

According to a further feature of the invention, an improved means for feeding the brim of a hat being worked to the action of the pouncing tools is provided. Referring to Figs. 2, 4 and 5, such brim feeding means includes upper and lower conical feed rollers 105, 106 affixed to inclined driving spindles 107, 108 journaled for rotation in bearings 109, 110 contained in upper and lower housings 111, 112, respectively. As best seen in Fig. 5, the upper housing 111 is hinged as at 113 to the lower housing 112 whereby it may swing in opening direction relative to the lower housing. The driving spindles 107, 108 are driven by bevel spur gears 115, 116 meshing above and below with an intermediate bevel worm gear 117 powered by the rotary core of a flexible shafting drive unit generally designated 118 (Fig. 2) which is supported adjacent its ends in brackets 119, 120, respectively. The driving or input end of the flexible shafting core carries a bevel spur gear 25a (Fig. 3) which meshes with the herein described power take-off worm 25 on the lower end of the motor shaft 21.

As seen in Fig. 2, the bracket 120 supporting the lower end of the flexible shafting unit is mounted from the motor frame extension casting 24. The bracket 119 supporting the upper end of the shafting unit is affixed to a tension adjusting U-frame 122 secured to the lower roller

housing 112 and embracing both of the roller housings. Disposed within the U-frame is a coil spring 123 reacting between the top face of the upper roller housing 111 and an adapter 124 carried at the end of a tension adjusting screw 125. The head 125a of the screw is formed as a hand-knob which may be conveniently turned to adjust the tension of coil spring 123 and thereby the gripping pressure exerted by the conical feed rollers 105, 106 on the opposite faces of a hat brim disposed therebetween. To provide for limited adjustment of the feed roller assembly as a unit, the bottom face of the lower housing 112 is provided with a longitudinal T-slot 127 adapted to receive the head of a clamp screw 128, the threaded end of which extends through a large-size hole in the head plate 15. Accordingly, the position of the feed roller assembly can be shifted both forwardly and rearwardly and laterally as well by a limited amount, as required to adjust its position with respect to the pouncing tools.

It will be understood that conical rollers 105, 106 are normally spaced by a small amount as determined by the spaced disposition of their driving spindles and the pressure of spring 123. To effect substantial relative separation of the feed rollers 105, 106, as required to present and withdraw the brim of a hat to and from their action, there is provided a vertically disposed roller separating pin 130 which is mounted for axial movement in and through the lower housing 112, and which is provided at its upper end with a head 131 positioned to engage against the under face of the upper roller housing 111. The pin is of length to extend downwardly through the horizontal head plate 15 and well into the machine housing 10. Accordingly, upon the pin being actuated in upward direction, its head 131 will abut against the upper roller housing 111 thereby to swing it upwardly by a limited amount about its hinge pin 113, such swinging movement being in opposition to the pressure of tension spring 123. Conversely, upon lowering of the pin, the upper housing 111 lowers in response to the pressure of the spring 123 to its working position in which its upper conical roller 105 is in brim feeding relation with respect to the lower roller 106.

According to a further feature of the invention, the separating and closing motion of the feed rollers is controlled by the foot treadle 80 and is moreover so inter-related with the relative separating and approach motion of the pouncing tools 28, 30 that separation of the tools is invariably effected prior to separation of the feed rollers and, conversely, closing of the feed rollers is invariably effected prior to closing of the tools. To this end, roller separating pin 130 is aligned with a mushroom shaped head 132 carried at the upper end of an actuating rod 133 vertically supported in upper and lower brackets 134, 134a and having its lower end threaded to receive the spaced adjusting nuts 135, 135a providing an operating and lost-motion connection between said rod and the inner end 87b of the lever 87. Accordingly, upon depression of the foot treadle arm 80 by a predetermined amount, the inner end 87b of lever 87 swings in upward direction to engage against nut 135, with continued lever motion actuating rod 133 and the separating pin 130 in upward direction. Consequent to such movement of the pin 130, the upper roller housing 111 is swung upwardly and roller 105 accordingly separates from lower roller 106. Upon release of the foot treadle, the inner

end 87b of lever 87 lowers, first under the urge of spring 123 and thereafter of spring 68, with the roller housing 111 of course lowering under the urge of spring 123.

Through proper dimensioning of the parts and positioning of adjusting nut 135, it will be seen that in the normal raised position of the treadle arm 80 both the tools 28, 30 and the conical feed rollers 105, 106 are in their closed working positions in which the tools engage against the upper and under surfaces of the brim of the hat being worked, and in which the feed rollers grip the brim to progressively feed it to the action of the tools. Upon depression of the treadle arm 80, the inner end 87b of lever 87 first engages the ball-point 90 as results in raising of the control rod 75 and separation of the tools. At this point in the arc of movement of the lever 87, its inner end 87b has not raised sufficiently as to effect engagement of roller separating pin 130 with actuating rod 133. However, further lowering of the treadle arm 80 results in the end 87b of the lever 87 raising by an amount such that it actuates rod 133 and thereby pin 130 in upward direction to effect separation of the feed rollers. With release of the treadle arm 80, the inner end 87b of the lever 87 disengages actuating rod 133 from the roller separating pin 130 prior to disengaging itself from the ball-point 90, with the result that the feed rollers invariably close prior to closing of the tools. The described interrelation of the opening and closing actuation of the tools and feed rollers makes an uneven sanding operation impossible, since it insures that feed motion is imparted to a hat brim prior to closing of the tools thereon. Moreover, the described control of both tool and feed rollers operation from a foot treadle leaves the operator's hands free to present and withdraw a hat brim to and from the action of the tools and feed rollers while the machine is in operation.

So that the machine may be left running, with both the tools and the rollers in their separated or non-active relationship, a treadle latch 138 is affixed to the side wall of the housing 10 adjacent the treadle arm and in position to engage the latter as it is depressed to its substantially full low position. The treadle arm may simply be released from the latch by a slight lowering thereof accompanied by foot pressure to the outside, whereupon the treadle arm automatically returns to its normal full raised position in which the tools and feed rollers are in their normal working position.

According to a further feature of the invention, the mounting of the pouncing tools 28, 30 on the free ends of the tool arms 32, 34 is such as to provide for angular adjustment of the tools about an axis which is transverse to the longitudinal axis of the arms. Referring to Figs. 3, 7 and 8, each of the tool arms is formed at its free end with a convex clamping face 140, and the mounting face of the tool body or casting is provided with a channel or groove 141 whose bottom wall 142 is concave and complementary to the convex clamping face 140. The width of the channel 141 is such that it receives the mounting end of the arm with sliding clearance only. As seen in Fig. 7, the tool casting is provided with longitudinally spaced steel inserts 143, 143a screwed thereto, the inserts being formed with a threaded bore receiving the ends of mounting bolts 144, 144a, operating in a longitudinal slot 145 (Fig. 1) provided in the mounting end of the arm. The

above described mounting permits of angular adjustment of the tools about a transverse axis since upon loosening of the bolts 144, 144a the tools can be slid forwardly or rearwardly relative to tool arm by a limited amount, the curvature of the mounting faces 140, 142 providing for a tilting or "cocking" of one or both of the tools. Such angular adjustment of tool to carrying arm is of advantage in that it permits setting of the opposed tools to a desired angular relationship of their working faces, that is to say, the tools may be set so that their working faces are in horizontal or inclined parallelism or are inclined to each other in directions as to effect heavier pouncing of the hat brim either along its inner or crown edge or along its outer edge, whichever is desirable.

A preferred means of securing the pouncing sheets or cloths to the tool body is also shown in Figs. 1, 7 and 8. As seen in Fig. 8, the tool body is provided along opposite edges with longitudinal recesses 147, 147a opening through its mounting face. The pouncing sheets are laid across the working face of the tool body and more particularly across the outer face of a felt pad 148 set into the tool body, the ends of the sheets being extended into the recesses. Clamping bars 149, 149a pivoted at their forward ends to the tool body operate in said recesses, and in their lowered or clamping position function to clamp the ends of the sheets against the recess bottoms. The clamping bars are each adapted to be releasably secured in clamping position by a locking lug or washer 150 carried on a threaded bolt 151, being swingable thereon from a locking to a bar clearing position. A wing nut 152 threaded on the bolt 151 serves both as a means to lock its lug 150 in clamp-bar securing position and to unlock the lug so that it may be swung clear of the clamp bar, whereupon the bar may be raised as required to replace a worn pouncing sheet, for example.

The above described mounting of the tools and abrasive sheets is also of advantage in providing for interchangeability both of tools and abrasive, as required for a machine capable of performing both back and front-shop finishing operations, and as desirable in obtaining a variety of brim finishes.

Preferably, the main housing, head casting and tool carrying arms are made from aluminum alloy castings, thereby to provide streamlined, lightweight construction throughout. Moreover, the main housing and its head casting have minimum dimensions consistent with design requirements, with the result that the machine as a whole requires small floor space and low floor loadings. Due to the mounting of the entire weight of the machine on rubber, vibration, as is likely to occur with high tool speeds, is substantially eliminated and the life of the machine is accordingly prolonged.

Without further analysis, it will be appreciated that the machine as described achieves the stated objects and other practical advantages in providing a hat brim pouncing machine capable of being operated at high tool speeds and which incorporates a novel and practical drive transmission from motor to pouncing tools and brim feeding rollers, and an effective and simply operated means of applying relative separating motion both to said tools and brim feeding rollers.

Moreover, the machine as described is simply operated and controlled through the provision of

a treadle actuated control capable of interrelating the separating and closing motion applied to both the tools and the feed rollers. This control is so organized as to leave the hands of the operator free to insert and withdraw the brims of the hats being worked to and from the tools and feed rollers, with the result that a high rate of production as well as efficient pouncing action is achieved.

- 10 As many changes could be made in carrying out the above constructions without departing from the scope of the invention, it is intended that all matter contained in the above description or shown in the accompanying drawings shall be interpreted as illustrative and not in a limiting sense.

I claim:

1. In a hat brim finishing machine, in combination, a pair of oppositely disposed finishing tools for operating on the opposite faces of the brim of a hat inserted therebetween, a pair of tool carrying arms, and means for imparting operating motion to said arms and hence to said tools including a rotary eccentric cam operatively related to each of said arms, means directly driving one of said cams and a splined driving connection extending between said cams and driving the other of said cams from said one cam.
2. In a hat brim finishing machine, in combination, a pair of oppositely disposed finishing tools for operating on the opposite faces of the brim of a hat inserted therebetween, a pair of tool carrying arms, and means for imparting operating motion to said arms and hence to said tools including a rotary eccentric cam operatively related to each of said arms, a drive shaft extending into and having a splined driving connection with one of said cams, and a splined driving connection extending between said cams and driving the other of said cams from said one cam.
3. In a hat brim finishing machine, in combination, a pair of oppositely disposed finishing tools for operating on the opposite faces of the brim of a hat inserted therebetween, a pair of tool carrying arms, means mounting said arms to provide both for tool motion in a closed, substantially elliptical path and for tool separating and approaching motion, and means for imparting the aforesaid motions to said tools including a rotary eccentric cam operatively related to each of said arms, means for driving one of said cams, and an axially extensible driving connection affixed to the other of said cams and driving the same from said one cam.
4. In a hat brim finishing machine, in combination, a pair of oppositely disposed finishing tools for operating on the opposite faces of the brim of a hat inserted therebetween, a pair of tool carrying arms, means mounting said arms to provide both for tool motion in a closed, substantially elliptical path and for tool separating and approach motion, and means for actuating said arms to provide the aforesaid tool motions including a rotary eccentric cam operatively related to each of said arms, a driving shaft directly driving one of said cams, and an axially extensible driving connection affixed to the other of said cams and driving the same from said one cam.
5. In a hat brim finishing machine, in combination, a pair of oppositely disposed finishing tools for operating on the opposite faces of the brim of a hat inserted therebetween, a pair of tool carrying arms, means mounting said arms to provide both for tool motion in a closed, substantially elliptical path and for tool separating and

approach motion, and means for actuating said arms to provide the aforesaid tool motions including a rotary eccentric cam operatively related to each of said arms, a driving shaft having a direct drive connection with one of said cams, and a floating shaft extension affixed to the other cam and having a splined driving connection with said one cam.

6. In a hat brim finishing machine, in combination, a pair of oppositely disposed finishing tools for operating on the opposite faces of the brim of a hat inserted therebetween, a pair of tool carrying arms, means mounting said arms to provide both for tool motion in a closed, substantially elliptical path and for tool separating and approach motion, and means for actuating said arms to provide for the aforesaid tool motions comprising a rotary eccentric cam operatively related to each of said arms, one of said cams being internally splined, a drive shaft having a splined driving connection with said one cam, a floating shaft extension affixed to the other cam and having a splined driving connection with said one cam, and means for applying separating and approach motion to the floating drive shaft extension relative to the drive shaft.

7. In a hat brim finishing machine, in combination, a pair of oppositely disposed finishing tools for operating on the opposite faces of the brim of a hat inserted therebetween, a pair of tool carrying arms, means for actuating said arms so as to cause the tools to move in a closed, substantially elliptical path and in opposite directions including a drive shaft and a shaft extension mounted for axial movement relative to said drive shaft, and means including the axially movable coaxially disposed shaft extension for applying relative separating and approach motion to the tools.

8. In a hat brim finishing machine, in combination, a pair of oppositely disposed finishing tools for operating on the opposite faces of the brim of a hat inserted therebetween, a pair of tool carrying arms, means for actuating said arms so as to cause the tools to move in a closed, substantially elliptical path and in opposite directions including a drive shaft and a coaxially disposed shaft extension mounted for axial movement relative to said drive shaft, said shaft extension supporting one of said tool carrying arms, and means for applying axial movement to the shaft extension thereby to impart relative separating and approach motion to the arms and tools carried thereby.

9. In a hat brim finishing machine, in combination, a pair of oppositely disposed finishing tools for operating on the opposite faces of the brim of a hat inserted therebetween, a pair of tool carrying arms, means for actuating said arms so as to cause the tools to move in a closed, substantially elliptical path and in opposite directions including a drive shaft having an axial bore and a shaft extension mounted for axial movement relative to the drive shaft, and means operative through the bore of the drive shaft for applying axial movement to the shaft extension thereby to impart relative separating and approach motion to the tools.

10. In a hat brim finishing machine, in combination, a pair of oppositely disposed finishing tools for operating on the opposite faces of the brim of a hat inserted therebetween, a pair of tool carrying arms, means for actuating said arms in such manner as to cause the tools to move in a closed, substantially elliptical path and

in opposite directions including a rotary eccentric cam carried by each of said arms, a drive shaft having a driving connection with one of said cams, a coaxially disposed shaft extension affixed to the other cam and having an axially extensible driving connection with said one cam, and means operative through the drive shaft and coacting with the shaft extension for effecting axial extension of its driving connection and a corresponding relative separation of the tools.

11. In a hat brim finishing machine, in combination, a pair of oppositely disposed finishing tools for operating on the opposite faces of the brim of a hat inserted therebetween, a pair of tool carrying arms, means for actuating said arms in such manner as to cause the tools to move in a closed, substantially elliptical path and in opposite directions including a drive shaft for driving one of said arms, and an axially movable shaft extension having an extensible driving connection with said drive shaft for driving the other of said arms, spring means reacting against one end of the shaft extension, and means operative against the other end of said shaft extension for effecting axial movement thereof with respect to the drive shaft and a corresponding relative separation of the tools against the pressure of said spring means.

12. In a hat brim finishing machine, in combination, a pair of spaced and oppositely disposed finishing tools for operating on the opposite faces of the brim of a hat inserted therebetween, a pair of tool carrying arms, means for imparting operating motion to said arms and hence to said tools including axially separable, rotary eccentric cams journaled for rotation in said arms intermediate the ends thereof, and means for adjusting the spacing between said cams.

13. In a hat brim finishing machine, in combination, a pair of spaced and oppositely disposed finishing tools for operating on the opposite faces of the brim of a hat inserted therebetween, means for imparting operating motion to said arms and hence to said tools including axially separable, rotary eccentric cams journaled for rotation in said arms intermediate the ends thereof, means for setting the spacing of the cams, and means for adjusting said spacing by calibrated amounts.

14. In a hat brim finishing machine, in combination, a pair of conical rollers adapted to grip a hat brim therebetween and to impart a rotary feed motion thereto, spindles mounting said rollers and being each journaled for rotation in complementary and hingedly connected upper and lower spindle housings, respectively, spindle driving means contained in said housings and said upper housing being mounted for separating and approach motion relative to the lower housing thereby to effect corresponding separation and approach motion of the rollers.

15. In a hat finishing machine, in combination, a pair of conical rollers adapted to grip a hat brim therebetween and to impart a rotary feed motion thereto, spindles mounting said rollers and being each journaled for rotation in complementary upper and lower spindle housings, respectively, spindle driving means contained in said housings, a hinge connection between said housings whereby the upper housing may swing relatively of the lower housing, and means for imparting swinging motion to said upper housing in both opening and closing direction thereby to effect corresponding separating and approach motion of the rollers.

16. In a hat brim finishing machine, in com-

13

bination, a pair of oppositely disposed finishing tools for operating on the opposite faces of the brim of a hat received therebetween, means for imparting operating motion to said tools, means for effecting separation of the tools so as to permit insertion and removal of the hat brim, a pair of feed rollers adapted to impart feed motion to the hat brim, means for effecting separation of said feed rollers so as to permit insertion and withdrawal of the hat brim, and means interrelating the action of said tool and roller separating means in such manner that the tools separate prior to the separation of the feed rollers and that the tools return to their normal working position subsequent to the return of the feed rollers to their normal working position.

17. In a hat brim finishing machine, in combination, a pair of oppositely disposed finishing tools for operating on the opposite faces of the brim of a hat received therebetween, means for imparting operating motion to said tools, means for effecting separation of the tools so as to permit insertion and removal of the hat brim, a pair of feed rollers adapted to impart feed motion to the hat brim, means for effecting separation of said feed rollers so as to permit insertion and withdrawal of the hat brim, a foot treadle, and means responsive to depression of the foot treadle for actuating both said separating means and for effecting the actuation of the tool separating means prior to the actuation of the roller separating means.

18. In a hat brim finishing machine, in combination, a pair of oppositely disposed finishing tools for operating on the opposite faces of the brim of a hat received therebetween, means for effecting separation of the tools so as to permit insertion and removal of the hat brim, a pair of feed rollers adapted to impart feed motion to the hat brim, means for effecting separation of said feed rollers so as to permit insertion and withdrawal of the hat brim, spring means operative normally to maintain the tools and feed rollers

14

in their closed or working position, a control treadle for actuating both said tool and said roller separating means, and means whereby depression of the treadle effects actuation of the tool separating means prior to the actuation of the roller separating means.

19. In a hat brim finishing machine, in combination, a pair of arms each mounting a finishing tool at its free end, the tools being disposed to operate on the opposite faces of the brim of a hat received therebetween, the mounting faces of the arms and tools being complementally convex and concave whereby the tools and their working faces may be inclined to the horizontal plane.

20. In a hat brim finishing machine, in combination, a pair of arms each mounting a finishing tool at its free end, the tools being disposed to operate on the opposite faces of the brim of a hat received therebetween, each said tool comprising a body having working and mounting faces and being provided with longitudinal grooves extending along the side edges of its mounting face, an abrasive sheet extending across the working face of the body with its ends extending into said grooves, clamp bars pivoted at their one ends and operative in their locked position to clamp the ends of the sheet against the groove bottoms, and releasable means coacting with the other end of the clamp bars for locking the clamp bars in their locked position aforesaid.

D. IVAN BEHMER.
